Specification for Design.

Patented July 11, 1922.

Application filed March 11, 1922. Serial No. 1,119. Term of patent 14 years.

To all whom it may concern:

Be it known that I, RICHARD M. GAFFNEY, a citizen of the United States, residing at the city of St. Louis, State of Missouri, have invented a certain new, original, and ornamental Design for a Combined Writing Pad and Advertising Device or Article of Similar Nature, of which the following is a specification, reference being had to the accompanying drawing, forming a part thereof.

The drawing illustrates a combined

writing pad and advertising device embodying my new design, Figure 1 being a front elevational view, Figure 2 being a rear elevational view, and Figure 3 being an edge view.

I claim:

The ornamental design for a combined writing pad and advertising device or article of similar nature, substantially as shown.

RICHARD M. GAFFNEY.
